Inventor
Edward Johnson Jr.

UNITED STATES PATENT OFFICE.

EDWARD JOHNSON, JR., OF CLEVELAND, OHIO.

IMPROVEMENT IN COOKING-STOVES.

Specification forming part of Letters Patent No. **36,714**, dated October 21, 1862.

To all whom it may concern:

Be it known that I, EDWARD JOHNSON, Jr., of Cleveland, in the county of Cuyahoga and State of Ohio, have invented new and useful Improvements in Stoves; and I do hereby declare that the following is a full and complete description of the construction and operation of the same, reference being had to the accompanying drawings, making part of this specification, in which—

Figure 1 is a perspective view, and Fig. 2 a vertical section.

Like letters refer to like parts in the different views.

The nature of my invention relates to constructing the stove-oven of corrugated sheet-iron, thereby accomplishing three important objects—namely, protecting the top of the oven from too great heat, compensating for the expansion and contraction of the metal, and enabling me to construct a durable and efficient cooking-stove wholly or in part of sheet-iron.

There is nothing peculiar in the form of my improved stove. It may be made in the form shown in the figures, or it may be varied in form. The bed-plate A in Figs. 1 and 2 may be made either of cast or sheet metal. Cast-iron is perhaps the most economical. The sides B and ends B' may be made of the same material or sheet-iron. The corrugated oven-plate C is made of one entire piece of plate of a width just sufficient to fill the space between the side plates. A double ledge or projection (seen at D D) serves to keep the

corrugated plate in place. By means of the corrugations the ashes that collect in the fire-box and upon the top of the oven serve to modify the heat radiated from the top plate of the oven. The oven-plate, being constructed as described, presents about twice the amount of radiating surface that would be presented by a flat plate, and hence a greater radiation of heat and the accomplishment of the desired object with a less amount of fuel.

As stoves are usually constructed, the fire-flue extends only upon three sides of the oven—namely, the top, the back, and the bottom. I have therefore in the construction of my improved oven-plate extended it only upon the three parts named. The front of the oven being narrow and furnished with no flue, it is not necessary to extend the corrugated plate over that part, for its extension there could serve no purpose, but it could be thus extended if found necessary to extend the fire-flue or fire-surface upon the front. I, however, disclaim the use of cast-iron corrugated plates for ovens, as also linings of sheet metal nor corrugated for ovens.

What I claim as my improvement, and desire to secure by Letters Patent, is—

Making the oven-plate of cooking-stoves of one entire piece of corrugated sheet-iron, as and for the purpose substantially as herein set forth.

EDWARD JOHNSON, JR.
